UNITED STATES PATENT OFFICE.

JAMES H. SKITT, OF PHILADELPHIA, PENNSYLVANIA, ASSIGNOR TO ROBERT E. SMITH AND GEORGE E. DRUM, BOTH OF PHILADELPHIA, PENNSYLVANIA, TRADING AS FIRM OF SMITH, DRUM & COMPANY.

AUTOMATIC GAS-BURNER-CONTROLLING MECHANISM.

1,132,883.

Specification of Letters Patent. Patented Mar. 23, 1915.

Application filed May 11, 1914. Serial No. 837,802.

To all whom it may concern:

Be it known that I, JAMES H. SKITT, a subject of the King of Great Britain, residing in the city and county of Philadelphia, in the State of Pennsylvania, have invented certain new and useful Improvements in Automatic Gas-Burner-Controlling Mechanism, of which the following is a true and exact description, reference being had to the accompanying drawings, which form a part thereof.

My present invention relates to machines employing intermittently operating gas burners, and the general object of my invention is to improve the means employed for automatically turning said burners on and off.

More specifically, the object of my invention is to provide a simple, effective and readily adjustable automatic burner control mechanism especially adapted for application to an existing type of hosiery singeing machine to start the appropriate gas burners as each stocking enters the singeing zone, and to extinguish the burner flames as the stocking leaves that zone.

The various features of novelty characterizing my invention are pointed out with particularity in the claims annexed to and forming a part of this specification. For a better understanding of the invention, however, and of the advantages possessed by it, reference should be had to the accompanying drawings and descriptive matter, in which I have illustrated and described a preferred form in which my invention may be embodied.

Of the drawings: Figure 1 is a partial front elevation of a stocking singeing machine to which my invention is applied; Fig. 2 is a partial side elevation, taken at right angles to Fig. 1; Fig. 3 is a sectional elevation of one of the controlling valves employed; and Fig. 4 is a side elevation of the form carrier.

The stocking singeing machine shown in the drawings is of a well known type in common use in which a continuously rotating member carries a set of stocking forms which are curved circumferentially about the axis of the said member and over which stockings are stretched during the singeing operation. As shown, the rotating shaft A of the machine is journaled in the side

frames X' and X² of the machine. The 55 form carrier B is secured to said shaft, and C are the curved stocking forms secured to the carrier B. As shown, the carrier B is formed with three arms B', each connected at its outer end through a bracket B² to one 60 end of each of two forms C which extend alongside of one another. The three forms C at each side of the machine are moved successively between an outer pair of singeing burners D and a corresponding inner 65 pair of singeing burners E. The four burners at each side of the machine receive a combustible mixture of air and gas from one of a corresponding pair of similar valves F and F^A. Each of these valves is formed 70 with a central air chamber F' and a surrounding gas chamber F². The latter opens at its lower end through an annular port F³ into an annular conical valve seat F⁴. A conical valve disk is adapted to engage the 75 seat F⁴, and then closes the port F³, as well as the lower end of the chamber F'. When the disk is moved down from the seat F⁴, the gas port F³ is opened on the initial movement of the valve, but the lower end of the 80 chamber F' does not open until the movement of the valve is sufficient to carry the cylindrical valve portion f² out of the chamber F'. On the closing movement of the valve, the air chamber is closed before the 85 port F³ is closed. The air and gas flowing from the chambers F' and F² into the mixing chamber F⁵, pass from the latter through suitable connections F⁶ to the corresponding burners D and E. A spring F⁷ 90 tends to hold each valve disk against its seat F⁴, and each valve disk may be moved away from its seat by means of a corresponding stem f'. Air is supplied to the air chambers F' of the valves F by pipes G, 95 and gas is supplied to the chambers F² through the piping H. Branch gas pipes h supply gas to the constantly burning pilot burners I, one adjacent each of the burners D and E.

The automatic valve controlling mechanism devised by me includes a bracket K, secured to one of the side frames, X', of the machine by bolts K'. In this bracket is journaled a cam shaft L, which at its inner 100 end carries a spur gear L' in mesh with a gear A' carried by the main shaft A, and which serves in the machine shown as one 105

of the driving gears for the shaft A. The number of teeth on the gears A' is preferably as many times the number of teeth on gear L' as there are form carrying arms B'.

- 5 At its outer end the shaft L carries two adjustable cams, M and N. The cam M is formed by three disks, M', M² and M³. The disk M' is keyed to the shaft L, and the disks M² and M³ are secured to the disk M' 70 by the bolt M⁴ passing through the slots M⁵ in the disks M² and M³. The disk M' is formed with a cam rise m', and the disks M² and M³ are formed with similar cam rises m² and m³, respectively. By virtue of 75 the pin and slot connection described, the cam disks M² and M³ may be adjusted relatively to the disk M' to vary the total cam rise of the cam M from its minimum circumferential length, which is the circumferential length of the cam rise m', up to its maximum length of approximately three times the circumferential length of the cam rise m. The cam N comprises parts N', N², N³, N⁴, N⁵, n', n² and n³, respectively. The bracket 80 25 K is formed with an arm K² receiving a stud K³ on which are journaled cam levers O and P. These are provided with anti-friction rolls, engaging the peripheries of the cams M and N, respectively. The levers O and P 85 30 are connected by connecting rods Q and Q', respectively, to rockers R and S. The rocker R is carried by a shaft T journaled in brackets X¹¹ and X¹² secured to the tops of the side frames X' and X², respectively. 90 35 The rocker S is secured to a sleeve U which is journaled in the bracket X¹¹ and surrounds and really forms a bearing sleeve for the shaft T. The sleeve U is provided with an arm U' adapted to engage the stem f 95 40 of the valve F, and the shaft T carries at its end remote from that at which the rocker R is secured an arm T', adapted to engage the stem f of the valve F^A.

- In the operation of the machine described, 45 stockings are placed on the various forms C, as each form approaches the position in which its front or toe end enters the singeing zone between the corresponding burners D and E. After passing through the singeing zone, each singed stocking is removed to make room for another stocking to be singed when the form is carried through the singeing zone the next time. As shown the ratio 50 of the gears A' and L' is three to one, so that 55 each of the cams M and N will make three complete turns for each turn of the shaft A; that is, will make one complete turn for each movement through the singeing zone of each stocking form at one side of the machine. 60 The gas is shut off from each set of burners, except when the appropriate valve F or F^A is held open by the engagement of the proper cam lever O or P with the rise of the corresponding cam M or N. This shutting off of the gas when not needed avoids 65

unnecessary gas consumption, and overheating of the parts, and is well known in the art to be generally desirable. Each of the cams M and N should be adjusted of course to insure the supply of gas to the burners 70 during the period required for a stocking to pass through the singeing zone, and this of course will depend upon the length of the stocking to be singed. With the construction described the cams may be readily adjusted, and may be adjusted independently, so that one length of stockings may be singed at the one side of the machine and another style of stockings of different length 75 at the other side of the machine at the same 80 time. The burner controlling mechanism described is obviously simple in construction and reliable in operation and is capable of ready adjustment to existing machines, not originally equipped with automatic burner 85 controlling mechanism. The valve disclosed, with the particular arrangement of air and gas ports and control thereof described and illustrated, has been found especially advantageous on account of the 90 sharpness with which the flame is cut off, the uniformity of the flame, and the quickness with which it reaches its full volume when the corresponding valve F and F^A opens.

Having now described my invention, what 95 I claim as new and desire to secure by Letters Patent, is:

1. In a singeing machine of the type described, the combination with the framework, rotating form carrier, and burners, of 100 a cam shaft journaled in said framework at one side of the machine and geared to said form carrier, a pair of independently adjustable cams mounted on said shaft, a rock shaft journaled in said framework and extending from one side of the machine to the other, a sleeve journaled on said rock shaft and in said framework at the side of the machine at which said cam shaft is located, 105 connections between said cams and said rock shaft and sleeve whereby said shaft is rocked by one, and the sleeve rocked by the other of said cams, a burner controlling valve at each side of the machine, an arm secured to said sleeve for actuating the adjacent valve and an arm secured to the rock shaft at the other side of the machine for operating the other valve. 110 115

2. In a singeing machine of the type described, the combination with the side frames, rotating form carrier, and burners, of a bracket attached to one side frame, a cam shaft journaled in said bracket and geared to said form carrier, a pair of independently adjustable cams mounted on said shaft, a pair of cam actuated levers also mounted on said bracket and co-operating one with one, and the other with the second of said cams, a rock shaft journaled in said frames and extending from one side of the 120 125 130

machine to the other, a sleeve journaled on said rock shaft and in the said side frame to which said bracket is secured, connections between said levers and said rock shaft and 5 sleeve whereby said rock shaft is rocked by one of said cams and the sleeve is rocked by the other cam, a burner controlling valve at each side of the machine, an arm secured to

said sleeve for actuating the adjacent valve and an arm secured to the shaft at the other 10 side of the machine for operating the other valve.

JAMES H. SKITT.
